UNITED STATES PATENT OFFICE.

HJALMAR ZAHL, OF DULUTH, MINNESOTA, ASSIGNEE, BY DIRECT AND MESNE ASSIGNMENTS, OF THREE-EIGHTHS TO CHARLES S. OLSON AND ONE-EIGHTH TO HENRY GUJER, BOTH OF DULUTH, MINNESOTA.

HOPPER-BOTTOM DUMP-CAR.

1,078,478.

Specification of Letters Patent.

Patented Nov. 11, 1913.

Application filed September 30, 1911. Serial No. 652,219.

To all whom it may concern:

Be it known that I, HJALMAR ZAHL, a citizen of the United States, residing at Duluth, in the county of St. Louis and State 5 of Minnesota, have invented certain new and useful Improvements in Hopper-Bottom Dump-Cars, of which the following is a specification, reference being had therein to the accompanying drawing.

10 My invention relates to improvements in hopper-bottom dump cars.

The object of my invention is to provide a car of this character which will carry the maximum load and at the same time having facilities whereby the load may be discharged with the least effort, in the shortest possible time.

Another object of my invention is to provide a car of this character in which the load 20 automatically dumps the car and provides means whereby the doors are easily returned to their closed position.

A still further object of my invention is to provide a car of this character having 25 great longitudinal strength to withstand the heavy strains to which such cars are subjected.

In the accompanying drawings forming part of the specification: Figure 1 is a side 30 elevation of my improved car. Fig. 2 is a vertical longitudinal sectional view of the chassis and hopper. Fig. 3 is a vertical transverse sectional view of the car. Fig. 4 is a longitudinal sectional view of the 35 door operating mechanism. Fig. 5 is a perspective view of the retaining dog of the door operating mechanism. Fig. 6 is a perspective view of the cylindrical pawl cam of the door operating mechanism. Fig. 7 40 is a perspective view of the pawl.

1 represents the car chassis and 2 the angle iron superstructure which supports the hopper 3, the lower discharge termini are intermediate the two sets of car wheels and 45 relatively near a level with the top of the railroad rails.

The chassis frame comprises the two side bars or angles 4, 4, and the central box-girder 5, all of which extend the entire 50 length of the car and form the main support thereof. The box-girder 5 is preferably built up of the two channel bars 6, 6, they being spaced apart and covered by the

plate 7, which latter is surmounted within the limits of the hopper, by the two inclined plates 8, 8, which meet at their upper edges and form baffles to assist in discharging the contents of the hopper when unloading.

The channel bars 6, 6, are spaced apart not 60 only to provide great strength, but for the purpose of housing the door operating drums 9, 9, 9, 9, which are revolvably mounted therein and which will be more fully described later.

The ends of the hopper 3 are preferably uniformly inclined their entire length, the side walls 3' being vertical from the upper edge of the car body to the point 11 where the remaining portion of the side walls are 70 pivotally suspended in any desired manner and forms the doors 12 of the hopper, their lowermost free ends being preferably operated by means of the chains 13 attached to said free ends and leading under the guide 75 rollers 14 and over the operating drums 9 to the operating mechanism 15. An I-beam 12' is formed integral with the lower edge of the doors 12 and project beyond the ends thereof and to which projection the operating chains 13 are attached, this being a convenient and practical means for reinforcing the door and providing the desired attachment.

The doors 12 are preferably formed with 85 the outwardly bulged angle 12'' therein to give greater capacity to the car and to provide the proper baffling effect to the load when being discharged which must occur between the limits of the railroad rails. 90 This angle is also formed so as to engage the side girders 4 of the car when the door is fully opened which latter becomes a support to the door when in such position.

The doors 12 are preferably suspended 95 from the vertical walls 3' of the hopper by bolts 16 loosely connecting the angle bar 17 securely attached to the lower edge of the vertical wall 3' and the angle bar 18 securely attached to the upper edge of the 100 door 12, thus a simple and durable hinged fastening is provided and the doors and side walls of the hopper may be reinforced with angle bars as desired.

Within the housing 15, which is securely 105 fixed upon the girder 5 and in line with the

rollers therein, operates the longitudinal ratchet 19 extending through both ends of the housing 15, the inner end 20 of which engages the door chains 13 and controls them. A retaining dog 21 is pivotally mounted within the walls of the housing 15 and astride the ratchet 19 and is designed to normally engage the teeth of the ratchet and lock it, the free end 22 of the dog having formed therein the vertically disposed elongated hole 23.

Within the diagonally opposite corner of the housing to that in which the dog 21 is mounted, is revolubly mounted the cylindrical pawl cam 24 pivotally carrying the pawl 25 which engages and operates the ratchet 19 when the cam is rocked by means of the removable hand lever 26 engaging either of the sockets 27 within the ends of 20 the cam 24.

A projecting lug 28 is formed upon the free end of the pawl 25 and pivotally engages a vertical link 29 which extends through the elongated opening or hole 23 in the dog 21 and pivotally connected at its upper end to the free end of the bell-crank lever 30 mounted upon the cross-shaft 31 within the walls of the housing 15, this shaft being operated by a suitable short hand lever 32 for disengaging both pawl and dog from the ratchet when desired.

The operation of the device is as follows: The doors being open as shown in Fig. 3, the cam 24 is rocked back and forth by the 35 hand lever 26 operating the pawl 25, which engages the ratchet 19 and thereby draw it to its innermost position and closing the doors, as shown in dotted lines Fig. 3, the dog automatically taking and keeping each 40 notch as the pawl feeds it along. The pawl is preferably prevented from disturbing the bell-crank 30 by the connecting holes in the link 29 being elliptical as clearly shown in Fig. 4, so that any reciprocation of the pawl 45 is not imparted to the crank 30. Now when it is desired to open the hopper and dump the load by allowing the doors to fall, the hand lever 32 is pressed down which will first raise the pawl 25 and free it from engagement with the ratchet 19, when a still 50 further depression of the lever 32 will lift and free the dog 21 by the pawl 25 engaging the under side of the free end 22 of the dog and lifting it, when the ratchet will be instantaneously freed and the door allowed to fall by gravity, thus quickly discharging the 55 contents of the hopper.

Having thus described my invention, what I claim is:

60 1. A hopper car comprising a central girder, extending the full length of the car, two side girders extending the full length of the car in a horizontal line therewith, a hopper supported by the girders and having its

ends extending a suitable distance below the same and a bottom having side portions adapted to form a portion of the side of the car when the bottom is open.

2. A hopper car comprising a supporting frame, a hopper supported by the frame and having its ends extending considerably below the frame, a bottom pivoted to the hopper above the supporting frame and having a portion thereof adapted to form a portion of the sides of the car when the bottom is open.

3. A car of the character described, comprising a hopper, hinged side walls forming the bottom of the hopper, a rack-bar flexibly connected to said hinged side walls, a pawl engaging said rack, a dog engaging the rack and holding the same, means for operating the pawl for moving the rack, and means for raising the pawl and simultaneously raising the dog out of engagement with the rack.

4. A car of the character described comprising a hopper, hinged bottom sections, a rack-bar, a flexible connection between the hinged bottom sections and the rack-bar, a pawl engaging the rack-bar, a dog engaging the rack bar and having one end extending over the pawl and provided with an opening, a link connected to the pawl and extending through the opening in the extended end of the dog, and means for operating said link whereby the raising of the pawl releases the dog.

5. A car of the character described, comprising a hopper, hinged bottom sections, a rack bar, a flexible connection between the hinged bottom sections and rack bar, an oscillating member, a pawl carried by said oscillating member and engaging the rack bar, a dog engaging the rack bar and having its free outer end extending above the free outer end of the pawl and provided with an opening, a link pivotally connected to the free outer end of the pawl and extending through the opening in the dog and a crank connected to the said link whereby the upward movement of the link releases the pawl from the rack and the continued upward movement thereof raises the dog out of engagement of the rack, substantially as shown and described.

6. A hopper car comprising a central hollow girder and two side girders extending the full length of the car, a superstructure supported by the center and side girders, a hopper within the superstructure and extending between the center and side girders, a portion of the sides of the hopper being loosely suspended and forming the bottom of the hopper, longitudinally and transversely mounted rollers within the central hollow girder, chains connected to the free lower ends of the suspended side portions

and extending from the longitudinal and transversely arranged rollers and extending on the outside of said hollow central girder, and means carried by the upper face of the 5 girder for operating said chains, substantially as shown and described.

7. A car of the character described, comprising a hopper, a hinged bottom, a rack bar flexibly connected to said hinged bottom, and a pawl and dog arranged to operate said rack-bar for operating the hinged bottom.

8. A car of the character described, comprising a hopper, a hinged bottom for the 15 hopper, a rack bar connected to said hinged bottom, a pawl engaging said rack, a dog engaging the rack and holding the same and

means for simultaneously operating the dog and pawl for the purpose described.

9. A car of the character described, comprising a hopper, a hinged bottom for the hopper, a rack bar flexibly connected to said hinged bottom, a pawl engaging said rack, a dog engaging the rack and holding the same, means for operating the pawl for moving the rack, and means for raising the pawl and simultaneously raising the dog out of engagement with the rack.

In testimony whereof I hereunto affix my signature in the presence of two witnesses.

HJALMAR ZAHL.
